SPLIT FLAP

Fred E. Weick, Langley Field, Va.

Application April 28, 1934, Serial No. 722,943

3 Claims. (Cl. 244—29)

(Granted under the act of March 3, 1883, as
amended April 30, 1928; 370 O. G. 757)

The invention described herein may be manufactured and used by or for the Government for governmental purposes, without the payment to me of any royalty thereon.

Among the devices for increasing the maximum lift coefficient over that obtained with a conventional wing, the one most commonly used has probably been the trailing-edge flap, which is deflected downward to increase the camber of the wing. Later developments resulted in the split-flap airfoil in which the rear portion of the airfoil is split into upper and lower sections and the lower section or flap deflected downward. In some instances, the flap is adapted to be moved to the rear as well as deflected downward in angle, giving in effect an increase in area as well as in camber.

In the recent application of flaps to airplane wings, it has been necessary either to use special ailerons (which have not been found as satisfactory as ordinary flap type ailerons) or to sacrifice a part of the performance desired from the flap, as by confining it to the portion of the wing inboard of the ailerons. As far as known, however, there has been no successful development, prior to the invention herein disclosed, of a combination of a high lift device and a device for the obtaining of lateral control which will give the full advantages of a well located split flap as well as those of conventional ailerons of narrow chord.

It is, therefore, an object of the present invention to provide an arrangement permitting the use of conventional ailerons together with a full-span split flap located in the most effective position for increasing the lift coefficient when deflected. This is accomplished by providing, in an airplane wing, the combination of conventional flap-type trailing edge ailerons and a split flap which, when retracted, fits into the under surface of the wing ahead of the ailerons but when extended has its trailing edge moved to the rear as well as downward so that it is approximately in the position giving the maximum lift coefficient.

In the drawing:

Figure 1 is a diagrammatic view of a tested Clark Y airfoil with split flap arrangement; showing flap size, axis location and flap angle most effective for obtaining the maximum lift coefficient.

Figure 2 is a view, in perspective, of an airplane wing embodying the combined split flap and conventional aileron arrangement of the present invention, the split flap being shown in retracted position.

Figure 3 is a similar view of the airplane wing, with the split flap in extended position.

Figure 4 is a sectional view on line 4—4 of Figure 2.

Figure 5 is a sectional view on line 5—5 of Figure 3, and

Figure 6 is a view showing a flap of modified cross section.

In determining the most efficient position of the split flap for increasing the lift coefficient of the wing tests were made on a model wing as part of a series on high-lift devices in the N. A. C. A. 7 x 10 foot wind tunnel. Lift, drag, and pitching moment were measured for a basic 10 Clark Y airfoil equipped with split flaps of three different sizes. Each flap could be rotated downward about an axis at its front edge. The tests were made with a range of angular deflections at each of several fore-and-aft locations 15 of the axis along the basic wing chord. The model wing had a chord of 10 inches and a span of 60 inches.

The three sizes of flaps tested had chord lengths of 0.20 c., 0.30 c., and 0.40 c.; c being the 20 chord of the basic wing. The 0.20 c. flap was tested with its axis at 0.80 c., 0.90 c., and 1.0 c. from the leading edge, the 0.30 c. flap with its axis at 0.70 c. to 1.0 c., and the 0.40 c. flap with its axis at 0.60 c. to 1.0 c., all with even 0.10 c. 25 intervals. The flaps could be locked in any angular position and the tests were made with the flaps deflected at 15° intervals, or less where necessary, over a sufficient range to determine the highest value of C_L max for each hinge location.

The highest lift coefficient obtained by depressing the split flaps with the flap axis in original location, that is—without moving the axis to the rear—was very nearly the same for all 35 three flap sizes and were somewhat higher than those given by conventional trailing edge flaps. With each size of flap, the maximum lift coefficient was increased as the flap axis was moved back to the 0.90 c. position. With the 0.20 c. 40 flap it continued to increase slightly as the axis was moved to the trailing edge, but with the larger sized flaps the values were slightly lower for the trailing edge axis location than for the one at 0.90 c. The highest values of C_L max for 45 the three flaps were found to be as follows:

Flap size	Highest C_L max	Axis location	Flap angle
0.20 c.	2.27	1.00 c.	68°
.30 c.	2.45	.93 c.	62°
.40 c.	2.52	.90 c.	54°

The highest value, which represents an increase of 98 per cent over the value of 1.27 for the plain wing, was obtained with the 0.40 c. flap.

The particular feature of the split flap airfoil, forming the subject matter of the present in-

vention, which is novel and different from previous ones, is the fact that ordinary ailerons are used over the same part of the span as a well-located split flap which may extend across the entire wing span. For present purposes, the invention will be described with reference to its embodiment in a basic Clark Y airfoil equipped with a split flap extending across the entire wing span and having a chord length of 40 per cent of the basic wing chord. The airfoil is provided with the conventional trailing-edge ailerons 2 of narrow chord and, as shown in Figures 2 and 4, the flap 3 when retracted fits into a recess 4 in the undersurface of the wing ahead of the conventional ailerons. The split flap shown in Figures 2 to 5 inclusive is of flat plate type beveled at the trailing edge and when closed it is flush with the lower surface of the airfoil. In this condition, the wing with ailerons operates in the normal manner of present conventional airplanes. If desired, the ailerons may be balanced to reduce the control forces by any ordinary means, such as the inset hinge.

When the split flap is deflected, to give lower speed and steeper glide for landing, it is moved to the rear, as shown in Figures 3 and 5, putting it in approximately the most effective location, as diagrammatically represented in Fig. 1, and also making it relatively easy to operate. Tests conducted in the 7 by 10 foot wind tunnel show that the conventional ailerons with any of the commonly used deflection linkages (equal up and down or differential) will give reasonably good rolling control at angles of attack below the stall with the flap deflected in the position shown.

One manner of supporting the split flap and guiding its motion in a suitable manner is illustrated in Figures 4 and 5 which show one of two or more similar supports that would be used at different places along the span. Each support includes separate converging rails or tracks 5 and 6 in the split portion of the wing ahead of the ailerons and a bracket 7 on the split flap fitted with two rollers 8 and 9 which run in the tracks 5 and 6. When some linkage (not shown) is used to push the flap to the rear, the rear portion of the flap is deflected simultaneously downward.

All of the better known combinations of high lift devices and devices for the obtaining of lateral control fall short of giving the full maximum lift coefficient. The split flap is, in general practice, located at the rear edge of the wing when retracted, making it impossible to use normal conventional ailerons on the portion of the wing covered by the flap. In split flap arrangements heretofore designed to permit the use of conventional ailerons, the latter have in some instances been pivotally mounted on a trailing portion of the flap and in other instances have been mounted in the usual manner on the wing with the split flap movable about an axis fixed at a distance forwardly of the trailing edge of the wing so that the flap, when retracted, fits in the undersurface of the wing ahead of the ailerons. Such an arrangement permits the use of conventional ailerons but the deflected flap is necessarily in an inefficient position for increasing the lift coefficient of the wing. It gives about the same advantage as the arrangement in which ordinary ailerons are used on the outer portions of a wing and the flap is confined to the portion of span inboard of the ailerons.

In the arrangement of the present invention, as herein disclosed and illustrated, the flap is not only retracted ahead of the ailerons permitting the use of conventional ailerons, but, when deflected is moved to the rear as well as downward and can be located in the most effective position for increasing the lift coefficient of the wing. Thus, it is the only arrangement permitting the use of conventional ailerons together with a full-span split flap located in the most effective position for increasing the lift coefficient when deflected. 5

The invention is not limited to a flap of the flat-plate type nor to any particular shape of flap. As shown in Fig. 6, the flap 32 may be of 15 airfoil section and located with a slight gap 10 between it and the main portion of the wing when the flap is deflected.

Having thus described the invention, what is claimed as new is:

1. An airplane wing having cut-outs in its trailing edge portion for the reception of conventional flap-type trailing-edge ailerons and having a rear portion forwardly of the cut-outs split to provide an upper rigid section and a lower 25 movable flap section, the said movable flap section being rotatable downwardly about an axis at its leading edge and having the flap axis movable to each of several fore-and-aft locations along the basic wing chord, including an 30 aft location in which the flap is deflected downwardly and directly below the ailerons with its leading edges substantially at the front edge of the cut-outs and its trailing edge disposed rearwardly beyond the cut-outs. 35

2. An airplane wing having cut-outs in its trailing edge portion for the reception of conventional flap-type trailing-edge ailerons and having a full span split flap fitting into the undersurface of the wing ahead of the cut-outs 40 when retracted, said flap being movable to the rear as well as downward when deflected to place it in angular position with its leading edge substantially adjacent the front edges of the cut-outs and with its trailing edge below and rearwardly beyond the trailing edge of the wing to provide a maximum lift coefficient without interference with the operation of the ailerons, and means within the wing and between the latter and upper surface of the split flap for supporting 45 the split flap and guiding its motions of retraction and deflection.

3. An airplane wing having cut-outs in its trailing edge portion for the reception of conventional flap-type trailing-edge ailerons and 55 having a full span flap on the underside of the wing having an original axis location along the basic wing chord forwardly of the trailing edge of the wing to permit the flap to be retracted into the wing ahead of the cut-outs, said flap being rotatable downwardly about its axis and shiftable to move the flap axis rearwardly to a position immediately forward of the said cut-outs, and means for supporting the flap and guiding its motion including separate converging 60 tracks fixed to the wing inwardly of the top and bottom, surfaces thereof and forwardly of the cut-outs at different places along the span and brackets on the upper side of the flap adjacent the leading edges thereof and provided with 65 rollers which run in the said converging tracks. 70
